United States Patent Office.

JACOB MILLER, OF CANTON, OHIO.

Letters Patent No. 72,523, dated December 24, 1867.

IMPROVEMENT IN HARVESTER-DROPPERS.

The Schedule referred to in these Letters Patent and making part of the same.

TO ALL WHOM IT MAY CONCERN:

Be it known that I, JACOB MILLER, of Canton, in the county of Stark, and State of Ohio, have invented certain new and useful Improvements in Droppers for Harvesting-Machines; and I do hereby declare the following to be a full, clear, and exact description of the same, reference being had to the accompanying drawings, making a part of this specification, in which—

Figure 1 represents a top plan of the material portions of a harvesting-machine, much of the detail being omitted, and which shows the dropper in place, and the mechanism for operating it from the driver's seat.

Figure 2 represents a section through the finger-bar and dropper, with the main frame and its several parts in elevation.

Figure 3 represents a view in elevation from the outside of the outer divider, showing the outside supporting-wheel, and means of hanging and adjusting it.

My invention consists in the particular manner of so connecting the dropper by means of rods, rock-shaft, and levers, with the main frame, as that the driver from his seat, by a long lever extending thereto, may operate said dropper by his hands, or by his feet, through a treadle separately connected, or by both at the same time, as may be convenient.

As my invention relates to the dropper alone, I shall particularly describe it, and omit any further description of the machine than is actually necessary to show the working of the dropper, the machine being sufficiently shown in the drawings for an understanding of its construction and general operation.

To enable those skilled in the art to make and use my invention, I will proceed to describe the same with reference to the drawings.

The driver's seat, A, is located upon the platform B, that usually covers the main frame C and working-gear of the machine. The dropper, as it is termed, consists of a bar, D, pivoted in rear of the finger-bar E, so that it can swing on its pivots, and having secured to it a series of fingers, F, projecting from it rearward. To the outside fingers of the series the two ends of a bail, a, are hooked by rings or dead-eyes, as at b b, the arms of said bail passing through guides e, or against friction-rolls d, to give them free and uncheckered motion as the dropper is raised up or let down. On the end of the bar D next the main frame there is fastened a lever-arm, e, to the upper end of which one end of a rod, f, is connected, the other end of said rod being connected at g to a long, bent lever, h, the upper end of which terminates in a handle, i, in close proximity to the driver's seat, so that the driver therein may readily seize and operate it. This lever h may be so bent as to form the rock-shaft j, which rolls in the bearings k k when the lever is operated, or if the rock-shaft j be made of a separate piece, then the lever h is connected to it. And the lever may be so further extended and bent as to form an arm, l, which arm is connected to a hinged foot-lever, m, on the platform, (so that the driver may, when in his seat, place his foot on said lever,) by means of a rod, n. When, however, a separate rock-shaft, j, is used, then this arm l may be a part of said rock-shaft, or attached to it, as may be found most convenient; or the pieces h i j l may be all formed out of one rod, suitably bent, and as shown in the drawings.

The driver, in his seat, may raise and let down the dropper at pleasure, by using, if he pleases, one or both of the levers h m, the former by the hand and the latter by his foot. When the dropper goes down to deliver the grain upon it, the bail by the same operation rises up to hold the falling straw and keep it separate from that which is being delivered on to the ground. When the dropper is raised up, the bail by the same operation falls down, and delivers what grain it had caught, and held whilst up, on to the dropper, whence it is delivered on to the ground, as before stated.

Having thus fully described the nature, object, and purpose of my invention, what I claim, is—

So uniting the dropper by means of rods and levers to the hand-lever i or h, and to the foot-lever m, as that the driver in his seat, by means of a long lever extending up thereto, may work the dropper by his hand, or by his foot, through a separate connection, or by both together, under an arrangement of parts, substantially as herein described.

JACOB MILLER.
